UNITED STATES PATENT OFFICE.

JAMES A. CARNEY, OF AURORA, ILLINOIS.

HEADLIGHT CONSTRUCTION.

1,273,148.

Specification of Letters Patent. Patented July 23, 1918.

Application filed January 31, 1917. Serial No. 145,735.

To all whom it may concern:

Be it known that I, JAMES A. CARNEY, a citizen of the United States, residing at Aurora, in the county of Kane and State 5 of Illinois, have invented certain new and useful Improvements in Headlight Construction, of which the following is a specification.

This invention relates to improvements in locomotive headlights, and has for its object to provide a headlight of a nature in which the source of illumination, preferably an electric light bulb or the like, may be readily adjusted axially of the reflector, or about the 15 axis of the reflector, to permit ready focusing of the rays.

Still another object is to provide a locomotive headlight which may be readily tilted to direct its rays at a desired distance 20 in front of the locomotive. These and other objects will be more fully set forth in the following specification and shown in the accompanying drawing, in which—

Figure 1 is a side elevation of my improved headlight.

Fig. 2 is a rear elevation of the same; and

Fig. 3 is a detail of the bulb-adjusting means.

Like numerals refer to like elements 30 throughout the drawings, in which 10 designates a base, from which projects upwardly the supporting yoke or bracket 11 rigidly secured to said base, and to a reflector 12 about the lower portion thereof, by screws 35 12^a or the like. A post 13, provided with an angularly disposed bottom portion 13^a, is attached thereto to the base 10 and projects upwardly therefrom. At its upper portion the post 13 is also angularly disposed to 40 form a horizontal arm 13^b, from which extends upwardly the adjusting rod 14, threaded at its lower portion, as indicated by numeral 14^a. The rod extends through a suitable aperture in the arm 13^b and is provided 45 with adjusting nuts 15 on either side of said arm and threaded on the rod 14. The latter is firmly screwed or threaded into a boss 16^a carried by the clamping ring 16, which is split at 16^b (see Fig. 2) and provided 50 with a threaded adjusting bolt 17 provided with a cross-bar 17^a for manual engagement. Proper rotation of the bolt 17 will operate to contract or expand the clamping ring 16, as will be apparent. Arm portions 16^c project forwardly from the clamping ring 16 and terminate in a ring 16^d, which is riveted,

brazed, or otherwise secured to the reflector 12, the latter being apertured within said ring 16^d to permit the projection there-through of the stem 18^a of a light bulb 18, 60 or other source of illumination. This bulb 18 screws into a socket 19, which in turn is carried by a sleeve 20 having a peripheral shoulder or ring 20^a which is suitably rounded on its outer surface to conform to the 65 surface of a portion of a sphere, the diameter thereof being substantially equal to the diameter of the interior of clamping ring 16, in which such shoulder fits and is adjustable; the shoulder in relation to the interior surface of the ring 16 forming a ball and socket joint. The sleeve 20 has a rear- 70 wardly extending portion 20^b, through which lead suitable current wires 21 and 22, respectively, leading to the binding-posts 23 75 and 24 carried by the post 13, and provided with wire-securing terminal portions 23^a and 24^a at the rear of the post 13.

An auxiliary bulb, or source of illumination, 25 is provided near the lower portion 80 of the reflector 12 in the interior thereof, the same being provided with wires 26 and 27 leading to the binding-posts 23 and 28, respectively, the latter being similar to posts 23 and 24, and provided with terminal post 85 portion 28^a at the rear of the bracket. Suitable current wires lead from the terminal posts 23^a, 24^a, and 28^a, and are connected to a suitable source of current through a proper switch, preferably located in the cab of the 90 locomotive and of well-known construction, operating to enable the engineer or other persons to close the circuit containing the main bulb 18 or the smaller bulb 25. The former furnishes the main source of illumination during driving of the locomotive or 95 other vehicle, while the smaller one is used while the locomotive is standing in the yard, or not in use, to prevent dazzling of the operators of other locomotives as well as waste 100 of current.

In use when the headlight is being adjusted after its attachment to the locomotive, the bolt 17 may be loosened, permitting expansion of the ring 16, and the bulb-carrying socket 20 may then be moved either longitudinally of its axis or about its center, by virtue of the ball and socket construction of the shoulder 20^a and ring 16, enabling ready focus of the rays of the bulb 110 projected from the reflector 12. After this focusing is obtained, the bolt 17 may be

quickly tightened by hand, securing the bulb in focused position. When it is desired to adjust the reflector to direct the rays thereof at a point a proper distance before the locomotive, the nuts 15 may be properly rotated to tilt the reflector 12 about the fixed yoke 11, either up or down as it is desired, and when the desired adjustment has been obtained, the nuts 15 will serve to retain the reflector in that position. When it is desired to remove the reflector, this may be easily done by disconnecting the light-wires from terminal posts 23^a, 24^a, and 28^a and thereafter removing the base 10 from the locomotive, the entire headlight being removable therewith.

It will be obvious that my invention is susceptible of modifications and improvements, and I do not wish to be restricted to the form shown and described except as defined in the appended claims.

What I claim is:

1. In combination, a reflector, a light element coacting therewith, a socket member carrying said light element and having a ball portion, and a clamping ring, the ball portion of said socket member being seated in said ring and being adjustable with

light element about a point or longitudinally with respect to said clamping ring. 30

2. In combination, a reflector, a light element coacting therewith, a socket member carrying said light element and having a ball portion, a clamping ring, the ball portion of said socket member being seated in said ring and being adjustable with said light element about a point or longitudinally with respect to said clamping ring, and means coacting with said clamping ring to secure said socket member in adjusted position. 35

3. In combination, a reflector, a light element coacting therewith, means carrying said light element, said means comprising a clamping ring, a second ring secured to said reflector, and a socket member having a ball portion seated in said first named ring and adjustable with said light element longitudinally in said ring. 40

In testimony whereof, I have subscribed, 50
my name.

JAMES A. CARNEY.
